CIRCUIT BREAKER BOX AND OPERATOR WITH IMPROVED LEVER AND INTERLOCK MEANS
Marshall G. Zavertnik, Manchester, Grace F. Horst, St. Louis, Joseph J. Farina, Bridgeton, George Linne, Florissant, and Charles E. Williams, Rock Hill, Mo., assignors to Killark Electric Manufacturing Company, St. Louis, Mo., a corporation of Missouri

Filed May 25, 1966, Ser. No. 552,957
10 Claims. (Cl. 200—50)

This invention relates to a circuit breaker box and operator which provides protection against hazardous gas and dust and which is waterproof and submersion-proof.

In general, this circuit breaker box and operator comprises a housing having a cover which may be hinged or otherwise fastened to the housing. An apparatus for mounting a circuit breaker and disconnect switches and an assembly for operating the circuit breaker are contained within the housing. An operating handle is located on the external side of the cover, and there are operating connections from the handle which are alternately engageable and disengageable with the operating assembly.

The mounting apparatus and operating assembly are designed to accommodate many different kinds and sizes of circuit breakers. The mounting assembly includes a mounting pan to which the circuit breaker is mounted, and the mounting pan is attached to the back wall of the housing in such a way that its position can be varied, depending upon the kind of circuit breaker being operated.

The operating assembly is mounted on a base plate that fastens to the mounting bolts which mount the circuit breaker to the mounting pan. The base plate has lugs with a plurality of holes in it for selective location of the operating assembly relative to the face of the circuit breaker so that the part of the operating assembly that engages the toggle of the circuit breaker is properly aligned. In the operating assembly, there is a trip lever that is guided by crank pins in vertical sliding movement. The circuit breaker toggle projects through a rectangular opening in the trip lever, and when the trip lever slides, the edges of the opening engage the trip lever and flip it between "on," "off," "trip" and "reset" positions. The trip lever is slid upon rotation of a crank arm. The crank arm is rotated when a shaft connected to the operating handle on the outside of the housing cover is properly located in slots in a shaft locator and is rotated. The crank arm is permanently attached to the shaft locator.

The shaft is properly positioned relative to the shaft locator only when the cover is closed, and a special interlock prevents opening or closing the cover unless certain slots in the interlock are aligned with the slots in the shaft locator, and these slots are aligned only when the operating mechanism and the circuit breaker toggle are in the "off" or "trip" positions. Therefore, the weatherproof and hazardous gas and dust protected housing cannot be opened unless the circuit breaker is off or tripped.

The general object of the invention is to provide a circuit breaker box and operator having the foregoing characteristics and advantages. Important particular objects are to provide a circuit breaker box and operator that is waterproof and protected against hazardous dust and gases and that has positive engagement between an externally located operating handle and a toggle operating assembly, with a special interlock in the positive engagement to prevent opening the housing unless the circuit breaker is switched off or tripped.

2

Another important object of the invention is to provide a circuit breaker box and operator with a mounting pan for supporting the circuit breaker and with an operating assembly for operating the circuit breaker from an externally located handle, wherein the mounting pan and the operating assembly are adjustable for adjustably mounting different kinds, shapes and sizes of circuit breakers, and wherein the shaft connection between the operating assembly and the operating handle is adjustable to accommodate different circuit breakers. An object is to provide a lock for the adjustable shaft which locks the shaft in the selected position against both longitudinal sliding and rotation relative to the operating handle, with a minimum number of parts.

Another object of the invention is to provide a circuit breaker box and operator wherein the operating assembly for the circuit breaker is within the housing or box and the operating handle is outside the housing with adjustable shaft connections between the handle and the operating assembly, and wherein the handle and the means for mounting the handle to the cover of the housing and the shaft provide weathertight and hazardous gas and dust protected connections.

Another object of the invention is to provide a circuit breaker box and operator with an operating assembly for preventing opening of the box unless the circuit breaker is in the "off" or "tripped" position, wherein the operating assembly is operated by an operating handle located outside the box to apply a lever action to a trip lever, and wherein the trip lever operates the circuit breaker toggle with only single-direction forces applied to the toggle.

Other objects and advantages will be apparent to those skilled in the art.

As shown in the drawings:

FIGURE 1 is a front elevation view of the circuit breaker box and operator;

FIGURE 2 is a side elevation view of the circuit breaker box and operator with parts broken away and shown in section;

Referring now to the drawings, this circuit breaker box and operator 30 comprises a housing 31 having a back wall 32, side walls 33 and 34, a top wall 35, and a bottom wall 36. There are mounting lugs 37 and 38 welded, bolted or cast to the back wall 32 with appropriate holes and slots to permit mounting of the box 30 to a wall. Also, threaded openings 39 and 40 extend through the top and bottom walls 35 and 36 of the housing 31 for receiving the threaded ends of conduits 41 and 42, respectively, which in turn may carry different electrical conductors to be attached to a circuit breaker mounted in the housing 31 as will be described.

The housing 31 has a front wall 43 surrounding a peripheral forwardly extending flange 44. A front cover 45 is fastened to a side of the front wall 43 by a piano hinge 46 or other fastener and has a short rearwardly extending peripheral wall 47 and outwardly extending peripheral flanges 48. A gasket 49 is secured to the cover 45, and, when the cover is closed against the housing 31, the gasket 49 bears against the flange 44 to provide a weathertight and gas and dust tight seal. The cover 45 is fastened tightly to the housing 31 by a plurality of bolts 50 which must be removed before the box can be opened.

A handle base 54 is fastened by bolts 55 to the front of the cover 45. The handle base 54 has a forwardly extending annular boss 56 and a rearwardly extending sleeve 57 that extends through a hole 58 in the cover 45. There is a bore 59 in the sleeve 57 and a counter bore 60 in the boss 56. A gasket 61 may be mounted between the handle base 54 and the cover 45.

A shaft section 63 extends through the bore 59 and has an enlarged head 64 positioned in the counter bore 60. The head 64 bears against the shoulder between the bore 59 and the counter bore 60 to restrict rearward movement of the shaft section 63, and a retaining ring 65 mounted in the shaft section 63 bears against the sleeve 57 and restricts forward movement of the shaft section 63. There is a recess 66 in the rearward end of the shaft section 63 and another shaft section 67 is slideable within the recess 66. A longitudinal groove 68 is formed in the shaft section 67. The shaft section 63 has two tapped holes 69 spaced 90° apart, as shown in FIGURE 15, through which a set screw 69' can be threaded for extension into the groove 68 to lock the shaft section 67 in place. The shaft section 67 has an enlarged conical head 70 at its lower end with a pin 71 extending transversely through the head 70. Because of the groove 68, the rotational position of the pin 71 relative to the shaft section 63 is fixed, but the shaft section 67 can be slid longitudinally when the setscrew 69' is loosened. An annular cutout 72 at the base of the head 64 of the shaft section 63 receives an O-ring 73 to provide water tightness.

In the head 64 of the shaft section 63, as best seen in FIGURES 14 and 15, there are two tapped holes 75 and 76 with counter bores 77 and 78, respectively. A handle 79 has bosses 80 and 81 that extend into the counter bores 77 and 78. The handle is fastened to the shaft section 63 by screws 82 and 83 received in countersunk holes 84 and 85 in the handle 79. A small round plate 86 is removably held in a tight fit within a shallow annular cutout 87 to cover the access to the screws 82 and 83.

The handle 79 has a skirt 89 that overlies the annular boss 56. The skirt 89 does not interfere with free rotation of the handle 79 relative to the hub 56 but it does provide protection against water leakage. There are suitable "on" and "off" (or "trip" and "reset") indicia 91 and 92 on the base 54 with a pointer 93 on the handle 79 to indicate the "on" and "off" (or "trip" and "reset") condition of a circuit breaker in the housing 31, as will be described. Also, the handle may have a conventional padlock lockout (or lock-on, not shown).

A circuit breaker mounting pan 100 is fastened to the back wall 32 of the housing 31 by two pairs of screws 101 and 102. The screws 101 extend through a transverse slot 103 in the mounting pan 100, and the screws 102 through a transverse slot 104. When the screws 101 and 102 are tightened, the plate 100 is held firmly in place against the back wall 32, but the plate 100 can be adjusted from side to side by loosening the screws 101 and 102.

Although this circuit breaker operator is designed to accommodate many different kinds and sizes of circuit breakers, as will be described hereinafter, a typical circuit breaker 105 is shown mounted in the housing 31. For this mounting, the circuit breaker 105 has four holes 106 through its body, each of which receives a hollow metal post 107. Each post 107 has a rearward end 108 and a forward end 109. The rearward end 108 of each post 107 either bears against the mounting pan 100, or extends to a "constriction" in the circuit breaker mounting holes 106. Holes 110 are tapped through the mounting pan 100. The holes 110 are located by the positions of the posts 107 and are aligned with the passages through the posts. For each post 107 there is a long screw 111 that extends through the post 107 and is threaded into the corresponding tapped hole 110. The circuit breaker 105 has a plurality of terminals 112 to which wires, carried by the conduits, are connected.

The internal operating assembly 115 comprises a base plate 116 which has a pair of upwardly extending lugs 117 and three downwardly extending lugs 118. There are several holes 119 through each of the lugs 117 and 118. Different ones of the holes 119 are aligned with the posts 107 depending upon the kind and size of circuit breaker 105 to be operated. The long bolts 111 pass through the appropriate holes 119 and into the posts 107 to fasten the base plate 116 to the circuit breaker body. The center 120 of the base plate 116 is raised toward the cover 45, as shown in FIGURES 5 and 7. There is an appropriate slot (not shown) through the base plate 116 through which the toggle 121 of the circuit breaker 105 extends and can freely operate. A pair of crank pins 122 and 123 are brazed or welded into the raised central portion 120 of the mounting plate 116. The shaft section 124 and head 125 of each crank pin projects in front of the base plate 116, as shown in FIGURE 21.

As shown in FIGURE 19, a trip lever 128 is formed in the general shape shown with a straight side 129 between a pair of upper and lower lugs 130 and 131. The trip lever 128 has a rectangular opening 132 in it and a long vertical slot 133. A relatively long crank pin 134 is brazed or welded into the trip lever 128 with its shaft 135 and head 136 projecting forwardly therefrom.

The trip lever 128 is mounted to the base plate 116 with its straight edge 129 bearing against the shafts 124 of the crank pins 122 and 123 and underlying the heads 125. Another crank pin 138 is threaded into the base plate 116 with its shaft 139 extending through the slot 133 in

the trip lever and its head 140 overlying the trip lever 128 and extending beyond the side edges of the slot 133. The toggle 121 extends through the rectangular opening 132.

The central section 120 of the base plate 116 has a round opening 144 in it in which an interlock 145 is mounted. As shown in FIGURES 16, 17 and 18, the interlock 145 has a cylindrical body 146 with tabs 147 that are bent over and welded to the base plate 116. The interlock 145 also has a narrow front wall 148 surrounding an angularly rearwardly extending flange 149 in which two slots 150 are cut.

A shaft locator 154 is shown in FIGURES 22, 23 and 24. The shaft locator has a cylindrical side wall 155 with an outwardly extending rim 156 at its base and an outwardly beveled mouth 157 at its front end. There is an annular shoulder 158 surrounding the beveled mouth 157. Slots 159 and 160 are cut in the opposite sides of the shoulder 158, the beveled mouth 157, and part of the side wall 155.

The shaft locator 154 fits within the interlock with the shoulder 158 overlying the front wall 148 of the interlock.

A compression spring 161 bears against the front wall 148 of the interlock 145 at one end and against a spring retainer 162 at the other end. The spring retainer 162 is held in place by a metal snap ring 163 that bears against the rim 156 on the shaft locator 154. This spring will allow the circuit breaker to be operated even if the shaft is slightly out of alignment.

A crank arm 164 is welded to the shoulder 158 of the shaft locator 154. As shown in FIGURES 8 and 9, the crank arm 164 has a round hole 165 through it with slots 166 and 167 at opposite sides of the hole 165. (See FIGURES 4 and 6.) The slots 166 and 167 are aligned with the slots 159 and 160 of the shaft locator 154. The crank arm 164 has a long arm 169 with a long slot 170 in it, the sides of which bear against the shaft 135 of the crank pin 134.

Operation

This circuit breaker box and operator is designed to operate the toggle 121 of the circuit breaker 105 between the "off" position shown in FIGURES 4 and 5 and the "on" position shown in FIGURES 6 and 7, as well as "trip" and "reset" positions. It is designed to accommodate many different kinds and sizes of circuit breakers 105 that may vary in longitudinal, lateral and height dimensions, and regardless of which kind of circuit breaker 105 is to be used, the mounting and operating apparatus can be adjusted in position to accommodate the circuit breaker for operation of its toggle 121 without disrupting its waterproof and hazardous dust and gas protection characteristics.

To install the circuit breaker 105, the mounting pan 100 is first installed by fastening the screws 101 and 102 to the back wall 32 of the housing 31. Before the screws are tightened, the mounting pan 100 is adjusted laterally for the proper position according to the kind of circuit breaker 105 to be operated. If necessary, the holes 110 which receive the long bolts 111 may be drilled and tapped in a number of different positions to accommodate different positions of the bolts 111 as determined by the location of the holes 106 through the body of the circuit breaker 105.

The operating assembly 115 is installed with the circuit breaker 105, and the operating assembly 115 is normally put together at the factory so that it need not be assembled in the field. This factory assembly includes welding the tabs 147 of the interlock 145 to the base plate 20 either before or after the crank pins 122 and 123 are installed. The crank arm 164 is welded to the shaft locator 154, and the flange end 156 of the shaft locator 154 is passed through the interlock 145 until the shoulder 158 seats against the front wall 148 of the interlock. Then the compression spring 161 is slid over the cylindrical side wall 155 of the shaft locator 154 followed by the spring

retainer 162 which can slide past the annular rim 156 at the back of the shaft locator 154. The snap ring 163 is snapped in place to retain the spring 161 and the spring retainer 162. Next, the trip lever 128 is positioned against the shaft 124 of the crank pins 122 and 123 and the crank pin 138 is installed through the slot 133. Installation of the crank pin 134 completes the assembly of the operating assembly 115.

The operating assembly 115 is installed with the circuit breaker 105 by sliding the posts 107 through the holes 106 in the body of the circuit breaker 105 and positioning the base plate 116 so that selected ones of the holes 119 are opposite the posts 107 as required to properly align the rectangular opening 132 in the trip lever 128 with the toggle 121 on the circuit breaker 105. Then the long bolts 111 are tightened in place. The shapes of the lugs 117 and 118 permit mounting of different circuit breakers in different positions, while permitting wire connections to the terminals 112 on the circuit breaker 105 without removing the base plate 116.

Once the handle base 54 is mounted to the cover 45 by the bolts 55, the shaft section 63 is slid through the bore 59 until the enlarged head 64 is within the counter bore 60, and the retaining ring 65 is snapped in place. The retaining ring 65 prevents longitudinal movement of the shaft section 63, while the O-ring 73 provides a water-tight shaft seal. If the shaft section 67 is too long, its end may be cut. Then the shaft section 67 is slid within the recess 66 until it projects a proper distance to locate the pin 71 against the bases of the slots 159 and 160 of the shaft locator 154 (see FIGURES 8 and 23). Then, when the setscrew 69 is tightened within the groove 68 against the shaft section 67, the shaft section 67 can neither slide longitudinally nor rotate relative to the shaft section 63.

It should be noted that the two 90° spaced tapped holes 69 for the setscrew 69' and the two mounting screws 32 and 83 permit the shaft section 83 and the handle 79 to be rotated in increments of 90° through 360° without disturbing the orientation of the circuit breaker or switch.

With the operating handle 79 fastened in place by the bolts 82 and 83, and the round plate 86 snapped in place, and with the conductors carried by the conduits 41 and 42 properly wired to the circuit breaker 105, the circuit breaker box and operator 30 is ready for use.

Since the interlock 145 is fixed in position relative to the base plate 116, it does not rotate when the shaft locator 154 rotates. The slots 159 and 160 in the shaft locator 50 are aligned with the slots 150 in the interlock 145 only when the toggle 121 of the circuit breaker 105 is in the down or "off" or "trip" position as in FIGURES 4 and 5. Only when these slots are aligned can the pin 71 on the shaft section 67 pass the inclined flange 149 of the interlock 145. With the slots 159 and 160 aligned with the slots 150, the cover 45 can be closed, at which time the conical head 70 is guided into the shaft locator 154 by the beveled mouth 157 as the pin 71 enters the slots 159 and 160. Once the cover 45 is closed, the bolts 50 are tightened in place to provide a weather-tight seal and protection against the passage of hazardous gas and dust.

Now the circuit breaker 105 is operated by rotating the operating handle 79 outside the housing 31. Rotation 65 of the handle in a counterclockwise direction as viewed in FIGURE 1 moves the pointer 93 to a position opposite the "on" indicator on the base 54. Since the pin 71 engages the sides of the slots 159 and 160 of the shaft locator 154, rotation of the handle 79 and the shaft section 63 and 67 causes the shaft locator 154 and the trip lever 164 which is welded to it, to rotate. Rotation of the trip lever 164 causes the sides of the slot 170 to bear against the shaft 135 of the crank pin 134 to slide the trip lever 128 vertically upwardly. The trip lever 128 is guided in a vertical direction by the crank pins 122

and 123 and the crank pin 138. The bottom edge of the rectangular opening 132 forces the toggle 121 to flip to the "on" position as illustrated in FIGURES 6 and 7. Clockwise rotation of the handle 79 to the "off" position reverses this sequence of operation to flip the toggle 121 to the "off" position illustrated in FIGURES 4 and 5. But before the handle is rotated to the "off" position to move the toggle to the "off" position, the cover 45 cannot be opened. With the mechanism in the "on" position, the slots 159 and 160 of the shaft locator 154 are not aligned with the slots 150 of the interlock 145, and the pin 71 is blocked by the inclined flange 149 from being withdrawn from the interlock 145. Therefore, a field operator cannot open the cover 45 until the mechanism is moved to the "off" position and the slots 159 and 160 are aligned with the slots 150.

Various changes and modifications may be made within the purview of this invention as will be readily apparent to those skilled in the art. Such changes and modifications are within the scope and teaching of this invention as defined by the claims appended hereto.

What is claimed is:

1. A circuit breaker box and operator comprising a housing for containing a circuit breaker or disconnect switch operable between "on" or "trip" and "off" or "reset" conditions, means to mount the circuit breaker to the housing, a circuit breaker operating assembly, means to mount the circuit breaker operating assembly in the housing in operative relation with the circuit breaker, a cover for the housing, operating handle means mounted on the external side of the cover and adapted to operatively engage the circuit breaker operating assembly when the cover is closed, and interlock means between the operating handle assembly and the circuit breaker operating assembly for preventing opening or closing of the cover unless the operating assembly is in a position corresponding to an "off" condition of the circuit breaker, the circuit breaker having a toggle movable between positions corresponding to the "on" and "off" or "trip" and "reset" conditions of the circuit breaker, the operating assembly comprising a shaft locator with operating connections between the shaft locator and the circuit breaker toggle to flip the toggle to "on" and "off" or "trip" and "reset" positions when the shaft locator is rotated, a slot in the shaft locator, the handle assembly including a handle and a shaft extending through the cover with a pin on the end of the shaft for entering the slot on the shaft locator to rotate the shaft locator when the shaft is rotated, the interlock means comprising a member stationarily mounted on the operating assembly and having a slot which is aligned with the slot of the shaft locator only when the shaft locator is in a position holding the toggle in the "off" or "trip" position, the interlock having a wall which prevents passage of the pin past it unless the slots are aligned.

2. The operating assembly of claim 1 wherein the shaft is adjustable in length to accommodate different kinds and sizes of circuit breakers.

3. The circuit breaker box operator of claim 1 wherein the handle assembly includes a handle, a base mounted on the cover for supporting the handle, the base having an annular boss extending away from the cover, the handle having a skirt overlying the boss.

4. The circuit breaker box and operator of claim 3 wherein the base has a sleeve extending through the cover, and the shaft extends through the sleeve, and a retaining ring on the shaft at the base of the sleeve to lock the shaft against axial displacement.

5. The circuit breaker box and operator of claim 1 wherein the shaft comprises two sections, one section having a recess in an end thereof for receiving an end of the other section, the latter section having a longitudinal groove in its side, and a setscrew in the recessed section for entering the longitudinal groove to lock the shaft sections together.

6. The circuit breaker box and operator of claim 5 wherein the recessed section has two tapped holes for selectively receiving the setscrew, and the recessed shaft section being connected to the handle with connecting means which permit 180° of rotation of the recessed shaft section relative to the handle, thereby permitting selective setting of the handle in 90° increments of rotation through 360° relative to the grooved shaft section.

7. A circuit breaker box and operator comprising a housing for containing a circuit breaker or disconnect switch operable between "on" or "trip" and "off" or "reset" conditions, means to mount the circuit breaker to the housing, a circuit breaker operating assembly, means to mount the circuit breaker operating assembly in the housing in operative relation with the circuit breaker, a cover for the housing, operating handle means mounted on the external side of the cover and adapted to operatively engage the circuit breaker operating assembly when the cover is closed, and interlock means between the operating handle assembly and the circuit breaker operating assembly for preventing opening or closing of the cover unless the operating assembly is in a position corresponding to an "off" condition of the circuit breaker, the circuit breaker having a toggle movable between positions corresponding to the "on" and "off" or "trip" and "reset" conditions of the circuit breaker, the operating assembly comprising a shaft locator with operating connections between the shaft locator and the circuit breaker toggle to flip the toggle to "on" and "off" or "trip" and "reset" positions when the shaft locator is rotated, the operating connections between the shaft locator and the toggle comprising a trip lever having camming edges for engaging opposite sides of the toggle, means to guide the trip lever in a single direction of movement only, parallel to the direction of swinging of the toggle between its "on" and "off" or "trip" and "reset" positions, a pin attached to the trip lever, and a crank arm attached to the shaft locator and engageable with the pin to slide the trip lever when the crank arm is rotated with the shaft locator.

8. The circuit breaker box and operator of claim 7 wherein the guide means for the trip lever comprises crank pins having shafts against which straight edges of the trip lever slide and having heads overlying edges of the trip lever to retain the trip lever in place.

9. A circuit breaker box and operator comprising a housing for containing a circuit breaker or disconnect switch operable between "on" or "trip" and "off" or "reset" conditions, means to mount the circuit breaker to the housing, a circuit breaker operating assembly, means to mount the circuit breaker operating assembly in the housing in operative relation with the circuit breaker, a cover for the housing, operating handle means mounted on the external side of the cover and adapted to operatively engage the circuit breaker operating assembly when the cover is closed, and interlock means between the operating handle assembly and the circuit breaker operating assembly for preventing opening or closing of the cover unless the operating assembly is in a position corresponding to an "off" condition of the circuit breaker, the circuit breaker mounting means comprising a mounting pan slidably adjustable in position on a wall of the housing to which it is mounted for accommodating different kinds and sizes of circuit breakers.

10. A circuit breaker box and operator comprising a housing for containing a circuit breaker or disconnect switch operable between "on" or "trip" and "off" or "reset" conditions, means to mount the circuit breaker to the housing, a circuit breaker operating assembly, means to mount the circuit breaker operating assembly in the housing in operative relation with the circuit breaker, a cover for the housing, operating handle means mounted on the external side of the cover and adapted to operatively engage the circuit breaker operating assembly when the cover is closed, and interlock means between

the operating handle assembly and the circuit breaker operating assembly for preventing opening or closing of the cover unless the operating assembly is in a position corresponding to an "off" condition of the circuit breaker, the operating assembly being fastened to the circuit breaker by bolts extending through a base plate of the operating assembly, the base plate having a plurality of holes for selection of ones through which the mounting bolts are to extend for selective location of the operating assembly according to the kind of circuit breaker to be operated.
